UNITED STATES PATENT OFFICE

N. W. WILLIAMS, OF FRANKFORD, PENNSYLVANIA, ASSIGNOR, BY MESNE ASSIGNMENTS, TO HIMSELF.

IMPROVED LAMP-BURNER.

Specification forming part of Letters Patent No. 35,860, dated July 8, 1862.

To all whom it may concern:

Be it known that I, N. W. WILLIAMS, of Frankford, (Philadelphia,) Pennsylvania, have invented an Improvement in Coal-Oil-Lamp Burners; and I do hereby declare the following to be a full, clear, and exact description of the same, reference being had to the accompanying drawings, and to the letters of reference marked thereon.

My invention consists in certain improvements(fully described hereinafter) in the burners of coal-oil lamps, said improvements being made with the view of dispensing with the usual glass chimney, preventing the smoke and disagreeable smell, and avoiding the complex passages and other appliances common to this class of coal-oil lamps.

In order to enable others skilled in the art to make and use my invention I will now proceed to describe its construction and operation.

On reference to the accompanying drawings, which form a part of this specification, Figure 1 is a vertical section of my improved coal-oil-lamp burner; Fig. 2, an exterior view of the cap, and Fig. 3 a sectional plan of the same.

Similar letters refer to similar parts throughout the several views.

A is a cover screwed into the orifice at the top of the reservoir B, containing the coal-oil, a portion only of this reservoir being shown in the drawings.

Through the cover A, which is hollow, passes the spindle C, on which are the usual wheels for raising and lowering the flat wick in the tube D, the latter being secured to the cover. This tube is carried upward to a greater length than those of ordinary lamps, and is surrounded by the elongated casing or cap E, the lower end, e, of which is enlarged and made flaring, so as to overhang the cover A, the rounded top having the usual oblong opening. The casing E is connected to the wick-tube D by means of the strips i, which are cut from the sides of the cap, bent inward, and notched at the ends, so as to fit to the opposite edges of the wick-tube to which they may be soldered, thereby maintaining the casing in its proper position in respect to the said wick-tube.

In coal-oil-lamp burners as heretofore constructed for the purpose of dispensing with the ordinary glass chimney, chambers for heating

the air admitted through perforations and contracted passages for directing the heated air to the flame have been deemed indispensably necessary to prevent smoke and the disagreeable smell which generally accompany the flame of coal-oil lamps.

I have found, after many experiments, that the most thorough consumption of smoke can be effected by the simple elongated casing or cap E, between which and the wick-tube is presented a chamber, F, the latter being entirely open below and presenting no obstruction to the free entrance of a plentiful supply of air, the progress of the latter upward being uninterrupted saving by the bent strips i, which occupy too insignificant a space within the chamber to arrest the current of air through the same.

The air admitted without stint or obstruction below becomes heated in the chamber F, and rushes with such force through the oblong opening f in contact with the flame as to cause the latter to burn with brilliancy and unaccompanied with the usual smoke and disagreeable smells.

Another important advantage gained by the casing with its unobstructed opening is the facility with which the lamp can be lighted, the application of the flame of a match to the top of the wick being all that is necessary to cause instant ignition, which cannot be effected in ordinary coal-oil lamps without considerable delay.

The flame of the lamp, too, may be reduced in extent without becoming extinguished, which is the result of a reduction of the flame of ordinary lamps; hence my improvement is especially applicable to lamps required for night use.

The covers of coal-oil lamps are generally so loose as to allow more or less leakage of the gases generated in the reservoir, these gases causing a disagreeable smell, which is avoided by my improved burner, the lower end of the exterior casing, E, being flared and overhanging the cover, so that all vapors passing from the reservoir at the point x will be carried with the air through the chamber F and consumed by the flame.

As regards the construction of my improved burner, it will be seen that it is of the most

simple and inexpensive character compared with other burners, in which the complex passages and appliances hitherto deemed necessary for a thorough consumption of the smoke demand tedious manipulation to manufacture and great care to adjust and maintain in proper order.

I claim as my invention and desire to secure by Letters Patent—

1. The exterior casing, E, with its oblong opening f, in combination with the elongated wick-tube D, when so arranged and connected together as to leave an unobstructed opening below for the free admission of air to the chamber between the casing and tube, as set forth, for the purpose specified.

2. Flaring the lower end of the casing E so as to overhang the cover A and permit the gases passing from the reservoir at the point where the cover is secured to the same to pass upward into the chamber P, as set forth.

3. Securing the exterior casing to the wick-tube by means of strips i, bent from and forming part of the said casing, as specified.

In testimony whereof I have signed my name to this specification in the presence of two subscribing witnesses.

N. W. WILLIAMS.
